US0D1111389S

(12) **United States Design Patent** (10) **Patent No.:** **US D1,111,389 S**
(45) **Date of Patent:** **** Feb. 10, 2026**

(54) **SHOE**

(71) Applicant: **SHENZHEN STARLINK
NETWORK TECHNOLOGY CO.,
LTD, Shenzhen (CN)**

(72) Inventor: **Jie Huang, Singapore (SG)**

(**) Term: **15 Years**

(21) Appl. No.: **29/886,792**

(22) Filed: **Mar. 13, 2023**

Related U.S. Application Data

(63) Continuation-in-part of application No. 29/758,548, filed on Nov. 17, 2020, now Pat. No. Des. 985,893.

(57) **CLAIM**

The ornamental design for a shoe as shown and described.

DESCRIPTION

FIG. 1 is a perspective view of a shoe showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines in the drawings depict portions of the shoe that form no part of the claimed design.

1 Claim, 8 Drawing Sheets
